(57) **CLAIM**

The ornamental design for a bug interception device, as shown and described.

DESCRIPTION

FIG. 1 is a top front perspective view of a bug interception device showing our new design;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top plan view thereof; and,

FIG. 7 is a cross-section view thereof, taken along the line 7-7 of FIG. 6.

The broken lines in the drawings illustrate portions of the bug interceptor device that form no part of the claimed design.

Views of the bug interceptor device that are not shown in the drawings form no part of the claimed design.
